UNITED STATES PATENT OFFICE.

HARRY COMSTOCK, OF MINEVILLE, NEW YORK.

PRIMER-RETAINER FOR DYNAMITE CARTRIDGES.

1,223,035.

Specification of Letters Patent. Patented Apr. 17, 1917.

Application filed February 6, 1917. Serial No. 146,967.

To all whom it may concern:

Be it known that I, HARRY COMSTOCK, a citizen of the United States, residing at Mineville, county of Essex, and State of New York, have invented certain new and useful Improvements in Primer-Retainers for Dynamite Cartridges, of which the following is a specification.

This invention relates to those devices designed for retaining the primer and fuse in a dynamite cartridge to prevent accidental detachment of the fuse and primer cap or detonator from the cartridge.

Various devices have been proposed for tying or securing the fuse to the cartridge. One method is the insertion of the cap on the end of the fuse into an opening leading in a general lateral or inclined relation into the dynamite within the shell and tying the 10 fuse to the shell. This method has the disadvantage of the fuse lying along the outside of the cartridge and in contact with the side of the hole; the string or cord is liable to slip off; if the cap is longer than the 20 diameter of the hole, it may become lodged crosswise thereof and if the cartridge is tamped hard in this position, it is liable to explode. The tendency of the tying cord to slip off renders the cap liable to pull out of 25 the cartridge and the tamping may break the cap or cause it to explode.

Another method heretofore proposed is to unfold one end of the paper shell and to insert the cap into a hole made lengthwise 30 of the dynamite. The opened end of the shell is then tied around the fuse by a cord. This method possesses the objection that the cap is easily pulled from the cartridge. The paper shell of a dynamite cartridge is 35 affined to render it waterproof; consequently, no matter how tight the cord may be drawn, the fuse readily pulls through the neck of paper at the end of the shell.

While this method places the primer or 40 cap in the proper position in the cartridge, the method of anchoring is unstable and therefore unsafe.

Another plan proposed is that set forth in the patent to William W. Jones, Number 50 1097442, May 19, 1914, wherein a retaining cord is inserted in the dynamite and provided with an adjustable device to engage the fuse. The cap in that construction is inserted from the top or end of the cartridge. While that device satisfactorily anchors the fuse and cap, the very great ex-

pense of placing this anchor in the dynamite and the incident increase in the cost of the cartridge is very objectionable and it appears to be impractical to apply the Jones 60 anchoring device in cartridges which are automatically made in large numbers on machines, the practice which commonly prevails at the present day. Such machines introduce dynamite into a large number of 65 paper shells simultaneously and afterward close the open ends of the shells. The introduction of the anchor of the Jones patent has to occur when the dynamite is being packed into the shell, a difficult and expensive operation.

To obviate the disadvantages inhering in the methods and devices above set forth, I have provided an improved primer and fuse retainer or anchor adapted to be tied to the 75 fuse to hold it and the cap firmly anchored to the cartridge. In my invention the cap and end of the fuse are introduced into an opening extending inwardly from the end of the cartridge, which is the safest position 80 for both cap and fuse.

In carrying out my invention I provide a retaining device, preferably of bell-shaped or flared form secured on the fuse and positioned so that, after opening or unfolding 85 the end of the paper shell, and inserting the cap in the dynamite, the said retaining device will be located within the mouth of the opened end of the shell and the said opened end may then be secured around the 90 retaining device by tying a cord around the shell. The invention may be carried out by the provision of a retainer which is crimped or otherwise secured on to the fuse, or, the end of the cap itself may be flared and the 95 flared end will be located within the opened end of the paper shell when the cap is embedded in the dynamite cartridge. The opened end of the shell may then be tied 100 around the flared end of the cap by using a cord. In either form of the invention, or in such modification as it may assume, the flared or bell-shaped retainer is secured on the fuse and, consequently, when the opened 105 end of the shell is tied around the retainer, the primed cartridge is securely connected to the fuse and cannot become detached therefrom.

I am aware that my invention is susceptible of modification other than that set forth without departing from the principle

thereof, and the embodiments hereinafter described and shown in the accompanying drawings are to be considered as illustrative rather than restrictive of the scope of the 5 invention.

In the drawings,

Figure 1 is a vertical section, partly in elevation, showing the complete primed cartridge except that the opened end of the shell 10 has not been tied around the retainer;

Fig. 2 a detail perspective of the end of the cartridge when the opened end has been closed and tied around the retainer; and

Fig. 3 a view like Fig. 2, partly broken 15 away, showing a modification.

The paper shell or cartridge 1 may be formed in any manner, a spirally wound shell being shown. The complete cartridge, as commonly supplied to the user contains 20 the dynamite 2 and has both of its ends folded. In Fig. 1 one of the folded ends is shown at 3, the other end 4 which was folded as is the end 3, having been opened after the insertion of the cap or detonator 5 which, 25 previous to insertion in the dynamite 2, has been crimped on a suitable length of fuse 6.

Referring to Figs. 1 and 2, I provide on the fuse 6 a retainer 7, preferably of metal, which is crimped on to the fuse in the same 30 manner that the cap 5 is crimped thereon and is located at a point where it will lie within the opened end 4 of the shell 1 when the cap 5 has been inserted in the dynamite 2 to a suitable depth. The retainer 7 is of 35 flared or bell-shaped form to prevent slippage thereon of the opened end 4 after the latter has been tied therearound by a cord such as shown at 8 in Fig. 2. I wish it understood, however, that I do not limit my 40 self to a bell-shaped or flared retainer 7, although that form is particularly adapted to carry out the purpose of the invention.

In Fig. 3 the cap 5 is shown as formed with a flared retainer end 7a such cap being 45 crimped on the fuse 6, as usual, and of such length that the flared end 7a will be disposed within the opened end 4 when the cap 5 has been inserted to a suitable depth in the dyna-

mite 2. A cord 8a is, like the cord 8, used for tying the end 4 of the shell around the 50 flared end 7a of the cap.

Having opened the end 4 and inserted the cap 5 into the dynamite at the point where the retainer 7, or 7a, is disposed within the opened end 4, the latter is then tied around 55 the retainer by using the cord 8 or 8a, thus securely anchoring the cartridge to the fuse 6.

A cartridge which has been primed in the manner set forth may be tamped into the 60 blast hole without danger of accidental discharge if ordinary precautions are observed, and there is little likelihood of the fuse and cap pulling out.

Having thus described my invention, what 65 I claim as new and desire to secure by Letters Patent is:—

1. A primer retainer for dynamite cartridges comprising means adapted to be carried by the fuse at a point where said 70 means will lie within an opened end of the shell when the cap or primer is in the dynamite, thereby permitting the opened end of the shell to be secured around said retainer.

2. A primer retainer for dynamite cartridges comprising a flared member adapted to be carried by the fuse at a point where said flared member will lie within an opened end of the shell when the cap or primer is in the dynamite, thereby permitting the 80 opened end of the shell to be secured around said flared member.

3. Means for priming a dynamite cartridge comprising a cap or primer, a fuse or the like, and a hollow flared retainer fastened on the fuse and located at a point where said retainer will lie within an opened end of the shell when the cap or primer is in the dynamite, thereby permitting the 85 opened end of the shell to be secured around said retainer, and a cord or the like for tying the opened end of the shell around said flared retainer.

In testimony whereof, I hereunto affix my signature.

HARRY COMSTOCK.
